(57) **CLAIM**

The ornamental design for a bundling device as shown and described.

DESCRIPTION

FIG. 1 is a perspective view of a first embodiment of a bundling device, showing our new design;

FIG. 2 is another perspective view thereof;

FIG. 3 is a first side elevation view thereof;

FIG. 4 is a second side elevation view thereof;

FIG. 5 is a third side elevation view thereof;

FIG. 6 is a perspective view of a second embodiment of a bundling device;

FIG. 7 is another perspective view thereof; and,

FIG. 8 is a side elevation view thereof.

The broken lines shown illustrate portions of the bundling device and form no part of the claimed design.
